UNITED STATES PATENT OFFICE

96,279

DESIGN FOR A SIFTER POWDER BOX

Paul E. Roehrich, New York, N. Y.

Application December 8, 1934, Serial No. 54,355

Term of patent 7 years

To all whom it may concern:

Be it known that Paul E. Roehrich, a citizen of the Republic of Germany and resident of New York city, in the county of New York and State of New York, has invented a new, original, and ornamental Design for Sifter Powder Box, of which the following is a specification, reference being had to the accompanying drawing, forming part thereof, in which, Fig. 1 is a perspective

view of the sifter powder box with the cap removed from its normally closed position, and Fig. 2 is a front elevational view of the assembly thereof showing my new design.

I claim:

The ornamental design for a sifter powder box, as shown.

PAUL E. ROEHRICH.
